ERASTUS B. HOFFMAN, OF HARRISBURG, PENNSYLVANIA.

HAND-SLOTTER.

1,160,286.

Specification of Letters Patent. Patented Nov. 16, 1915.

Application filed May 29, 1914. Serial No. 841,943.

To all whom it may concern:

Be it known that I, ERASTUS B. HOFFMAN, a citizen of the United States, residing at Harrisburg, in the county of Dauphin and State of Pennsylvania, have invented a new and useful Hand-Slotter, of which the following is a specification, reference being had to the accompanying drawings and to the letters and figures of reference marked thereon.

This invention relates to a tool or implement that is designed to be used by mechanics or others, more especially on repair work, the invention having reference more particularly to a tool that is adapted to be handled and operated by hand for cutting slots in metal, preferably for cutting slots of different widths.

An object of the invention is to provide an improved hand slotter having a plurality of removable slotter blades which may be used on different kinds of metal, so that one blade may be reserved for use on metal requiring sharp cutters and not likely to dull the cutters while other blades may be reserved for use on other metals, in order that the workman may have a convenient and always ready tool at hand for slotting purposes.

A further object of the invention is to provide an improved hand slotter which shall be so constructed as to enable the workman to cut slots of different widths at will as may be required, so as to obviate the necessity of keeping at hand and entailing the expense of a number of slotters in order to do a variety of work.

A still further object is to provide an improved frame for securely holding a plurality of slotter blades and permit ready removal and replacement of the blades, and which shall be so constructed as to be convenient for use, cheaply produced and efficient and economical in use.

With the above-mentioned and other objects in view, the invention consists in an improved hand slotter having a plurality of slotter blades which are removably connected to a frame adapted to tightly hold the blades, the blades preferably differing in thickness in order that slots of different widths may be cut by the tool or implement.

The invention consists also further in the novel parts, and in the combinations and arrangements of parts, as hereinafter par-

ticularly described and further defined in the appended claims.

Referring to the drawings, Figure 1 is a perspective view of the improved hand slotter as preferably constructed. Fig. 2 is a transverse section of the slotter frame minus the slotter blades approximately on the plane indicated by the line A A in Fig. 1. Fig. 3 is an end elevation of the slotter. Fig. 4 is a longitudinal central section of the slotter partially broken away, the more important parts or features being on an enlarged scale in the interest of clearness. Fig. 5 is a plan view of two of the coöperating parts of the slotter frame. Fig. 6 is a perspective view of one of the parts of the slotter frame designed for tightening the blades in the frame or to be adjusted to permit of removal of the blades.

Similar reference characters in the different figures of the drawings indicate corresponding elements or features of construction herein referred to and described.

As preferably constructed the improved slotter frame comprises a main bar or rod 1 provided on one end portion with a suitable handle 2 which preferably has a ferrule 3 thereon, the handle and its ferrule being suitably secured to the bar, preferably by means of a pin or rivet 4, or otherwise as may be desired. The bar 1 is suitably provided with a collar 5 which preferably is formed separately and suitably secured to the bar, preferably by means of a pin or rivet 6 and in a position adjacent to the inner end of the handle, the collar being adapted to constitute a head coöperating to carry one end of the slotter blades. The remaining end portion of the bar 1 is provided with screw threads 7, and it is incased by a sleeve 8 constituting an adjusting nut which has screw threads 9 therein that co-operate with the screw threads 7, the outer portion of the sleeve having flat faces 10 and 11 adjacent the outer end of the sleeve to enable the sleeve to be turned by means of a wrench, the inner end portion of the sleeve preferably having a smooth bore 12 adapted to clear the screw threads 7 and fit closely on the main portion of the bar 1 which is cylindrical. The inner end of the sleeve has a head 13 thereon of sufficient diameter to constitute a guide collar, and a cylindrical guide 14 is formed on the sleeve adjacent to the collar, being a relatively

smaller portion of the head. The collar portion of the head has a face 15 extending outward from the guide 14 and also a shoulder 16 forming the under side of the head and from which screw threads 17 extend that are formed on the exterior of the sleeve 8. A nut 18 is placed on the sleeve and co-operates with the screw threads 17, or the nut may be otherwise secured to the sleeve so as to constitute a collar adjacent to the face 16 and extending outward opposite to the face 15 so as to form a guide channel between the nut or collar and the relatively large portion 13 of the head.

15. Two spreader plates or frame members 19 and 20 are provided which preferably are disk-like in form and identically alike, each plate or member having a central circular aperture 21 therein, one of the plates being 20 suitably connected with the collar 5 so as to constitute a portion of the slotted frame, the collar preferably having a cylindrical guide seat 22 extending to a shoulder 23 disposed opposite to the inner end of the handle 25 with space between in which the plate 19 is arranged, the aperture in the plate receiving the guide portion 22, this arrangement permitting the two plates to be economically made alike. The plate 19 may be so fitted 30 as to be rotatable on the collar 5 if desired, or the plate may be rigidly fixed relative to the collar or to the handle of the frame, and it is obvious that the plate or member 19 need not of necessity be a separate element 35 of the frame. The companion plate 20 is placed upon the guide 14 which is rotatable in the aperture 21, the plate being between the shoulder or face 15 and the collar or nut 18, which permits the sleeve 8 to be rotated 40 in the plate. One plate has a plurality of radially arranged slots 24, 25, 26 and 27 extending from the periphery thereof, the companion plate having an equal number of similar slots 24', 25', 26' and 27'. In the 45 most perfect design of the slotted frame the slots differ in width, one slot being sufficiently broad to receive the thickest slotted blade that may be desired, another slot being slightly less in width, another being still 50 less, and the remaining slot still less in width, so that a variety of blades are accommodated in the frame. Suitable provision is made for retaining the slotted blades in the frame, two wire rings 28 and 55 29 preferably being employed, the rings having gaps 30 and 31 therein respectively through which the thicker one of the blades may be passed.

The slotted blades may be of well known 60 form or may be specially constructed, as may be desired, a thick or broad blade 32 having saw teeth 33 being employed, the blades having holes 34 and 35 in opposite end portions respectively to receive the respective retaining rings, another blade 36

having teeth 37, a blade 38 having teeth 39, and still another blade 40 having teeth 41 being employed, each blade being different in thickness and adapted to fit closely into the slots formed in the frame plates and into 70 which the blades are placed with the backs of the blades seated on the bottoms of the slots. With the adjusting sleeve 8 properly adjusted the retaining rings are turned so as to pass through the holes in the blades so 75 that the blades are retained in the slots by the rings which are arranged on the outer sides of the plates 19 and 20. The sleeve 8 or adjusting device is screwed outward so as to move the plate 20 in the direction away 80 from the plate 19, with the result that the retaining rings are drawn tightly against the outer sides of the plates and cause tensile strain on the slotted blades. In case there be slight inaccuracy in the spacing between the holes 34 and 35 the blades nevertheless are drawn tightly because of the possibility of the plates 19 and 20 yielding slightly, being preferably composed of 85 spring steel, so that practically uniform tension is placed on all the blades and prevents the blades from springing laterally when in use.

It should be understood that while the blades are preferably retained at either end 90 so that they cannot fall out of the slots when loose, by a single ring or device, other equivalent means may be adopted for the purpose and which will permit the use of the slotted in case of breakage and removal of 100 one or more of the blades, the retaining rings shown also enabling the frame to carry less than the preferred number of blades in emergency. Various other modifications may be made also within the scope of the 105 accompanying claims.

In order to use the improved slotted the handle 2 is held in one hand and the sleeve 8 in the remaining hand of the workman and thus conveniently guided and operated 110 upon such work as may require slots for receiving screw drivers, or for forming key seats or grooves for various purposes, the tool being moved forward and backward, as when operating a hack-saw, the slotted 115 obviously being adapted to be used in some cases as a hack-saw if desired, the thinner or narrower blades being most suitable for cutting off metal, as will be understood, and the different blades are used for cutting slots 120 which may be required of the width corresponding to the thickness of the blade.

Having thus described the invention, what is claimed as new is—

1. A hand-slotted frame including a main 125 bar and two frame members on the bar having each a plurality of slots to receive apertured slotted blades, and two retaining rings having each a gap therein to receive the blades, the rings being adapted to be insert- 130

ed in the apertures of the blades for coupling the blades together and retaining them in the slots.

2. In a hand-slotter, the combination with 5 a plurality of slotter blades having each a hole in each end portion thereof, of a frame comprising a main bar, two disks on the bar having each a plurality of slots to receive the blades, two retaining rings coöoperating 10 with the two disks respectively and extending through the holes in the respective ends of the blades, and means for forcing the disks apart.

3. In a hand-slotter, the combination of a 15 main bar having screw threads on one end portion thereof, a handle fixedly secured to the opposite end portion of the bar, a frame member extending about the bar adjacent to the handle and secured to the bar, said member having a plurality of slots in the outer portion thereof, a sleeve rotatable on the bar and having internal screw threads engaging the screw threads of the bar, the sleeve having also a collar on its inner end, the outer 25 end of the sleeve having a handle portion thereon, a frame member rotatively mounted on the sleeve adjacent the collar and having a plurality of slots in the outer portion thereof, a plurality of slotter blades seated 30 in the respective slots of the frame members, each blade having openings to receive coupling rings, and non-continuous rings arranged on the outer sides of the frame members in the openings of the blades for coupling 35 the blades together and retaining them in the slots.

4. In a hand-slotter, the combination of a main bar having screw-threads on one end portion, a handle fixed on the opposite end

portion of the bar, a collar fixed on the bar 40 adjacent to the handle, a frame member extending about the bar and retained by the collar to the handle, said member having a plurality of slots differing in width in the peripheral portion thereof, a sleeve having 45 screw-threads engaging the screw-threads of the bar, the inner end portion of the sleeve having a collar and a cylindrical guide adjacent to the collar and having external screw-threads thereon adjacent to 50 the guide, the outer end portion of the sleeve being constructed to constitute a handle portion and to be engaged by a wrench, a nut engaging the external screw-threads and seated against the outer side of the 55 guide, a frame member rotatively mounted on the cylindrical guide between the nut and the collar of the sleeve and having a plurality of slots differing in width in the peripheral portion thereof, a plurality of slotter 60 blades differing in thickness and corresponding respectively to the different slots of the frame members and seated therein, each end portion of each blade having an opening therein to receive a retaining ring, and two 65 non-continuous rings arranged on the outer sides of the two frame members respectively and normally extending across the slots therein and also through the adjacent 70 openings of the blades for coupling the blades together and retaining them in the slots.

In testimony whereof, I affix my signature in presence of two witnesses.

ERASTUS B. HOFFMAN.
